UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed March 5, 1928. Serial No. 259,163.

My invention relates to a slicing machine which shall be light, simple to manufacture, efficient and easy to operate. One purpose of my invention is the provision of a slicing machine of the type described, wherein a particularly accurate adjustment of the gauge plate is possible. Another object is the provision of means for adjusting the gauge plate in relation to the opposed meat carrier. Another object is the provision of means for 10 adjusting the gauge plate to mask the otherwise exposed edge of the rotary knife and to permit ready cleaning of the gauge plate. Another object is the provision of means for 15 moving the gauge plate angularly toward and away from the knife and for preventing movement of the gauge plate when adjusted.

Other objects will appear from time to time in the course of the specification and claims. 20 I illustrate my invention more or less diagrammatically in the accompanying drawings, wherein—

Figure 1 is a rear elevation;
Figure 2 is an end elevation;
25 Figure 3 is a plan view on an enlarged scale with parts in horizontal section;
Figure 4 is a fragmentary view similar to Figure 3 with parts in different positions;
Figure 5 is a section along the line 5—5
30 of Figure 3;
Figure 6 is a section on the line 6—6 of Figure 3;
Figure 7 is a section on the line 7—7 of Figure 3;
35 Figure 8 is an elevation of a variant form; and
Figure 9 is a side elevation with parts in section.

Like parts are indicated by like symbols 40 throughout the specification and drawings.

A generally indicates any suitable base frame or member provided for example with anti-frictional and noise-deadening studs or pads A¹.

45 Mounted upon such base member is any suitable motor means, herein shown as the motor B, from which projects the motor shaft B¹ on which is the driving pulley B² adapted to engage and drive the belt B³ herein shown 50 as of wedge shaped cross-section to engage

the inclined faces of the channel B⁴ on the pulley B².

C is an upwardly projecting housing or frame member mounted upon the base A and including the shield portion C¹ and the knife supporting sleeve C². 55

Rotatably mounted within the sleeve portion in any suitable manner is the knife shaft D which carries a channeled pulley D¹ adapted to receive about it the belt B³. 60

E is a knife disc secured to the enlarged end portion D⁴ on the shaft D for example by the screw E¹ and additionally secured against rotation for example by the screws E². The, knife disc is shown as convex and is peripherally cut away or recessed on its hollow face as at E³ to leave a peripheral projection E⁴. 65

Mounted on the forward face of the frame member C is the fixed guard plate F. At its left edge, as shown in Figure 1, it is arcuately cut away as at F¹, the arcuate portion penetrating or seating closely within the depression E³ of the knife E, the axis of the knife being slightly tilted in a horizontal plane from perpendicularity to the plate, as 70 shown in Figure 3, to bring the edge of the knife forward into the position shown in such figure, generally in the plane of the guard plate F. 75

G is a track, herein shown as of circular 80 cross-section, mounted for example on the supports G¹ upwardly projecting from the opposite ends of the base A. Aligned beneath the track G is any suitable slide or rail G², herein shown as of rectangular cross- 85 section.

Mounted for movement along the track G and the rail G² is any suitable carriage or supporting member herein shown as including a body portion H and a meat engaging member H¹ such meat engaging member including a broad face H² slightly inclined to the horizontal and a narrower face H³ sharply inclined to the horizontal, the two being generally perpendicular to each other. Downwardly depending from the body portion H is an arm or slide H⁴, with a depending finger H⁵ adapted to engage one side of the slide G². Removably secured to the arm H⁴ is a finger or enclosing member H⁶ in which is any 95 100

suitable adjusting member, herein shown as a screw H^7 controlled by a lock nut H^8 adapted to engage the opposed side of the slide G^2 . H^{10} are any suitable buffer members adapted to contact the posts G^1 at each end of the excursion of the carriage, and H^{12} is any suitable handle for the manual movement of the carriage.

J is a face plate or pusher provided with a handle J^1 and guide pins J^2 , said guide pins being in alignment with and received by apertures J^3 in the carriage H .

K is a frame or housing member upwardly projecting from the base A . Said housing may be integral with the base as shown and may carry any suitable control switch I for controlling the current to the motor B . The walls of the generally rectangular shaped housing member K are provided with an inwardly projecting irregularly shaped flange K^1 , the purpose for which will later appear.

L generally indicates a gauge plate proper, including an upwardly extending gauge plate L^1 , the surface of which may be slightly convex or bowed to conform to the cutting edge of the knife E since the cutting portion of the knife, due to the angle at which it is set, is not in a vertical plane but is slightly bowed forward. The right edge of said gauge plate as shown in Figure 1 may be arcuately formed as at L^3 generally concentrically with the arcuate portion F^1 of the fixed guard plate. L^4 is a laterally projecting housing integral with the gauge plate L^1 which supports an inwardly projecting irregularly shaped flange L^5 said flange being generally at right angles to the vertical gauge plate. The flange L^5 is provided at its lower face with two elongated bosses L^6 adapted to engage the opposed bosses M^1 of the member M , secured to each other by screws M^2 . The member M is dished as at M^3 to form an oil pocket and is provided with a plurality of upwardly projecting bearings M^4 M^5 M^6 and M^7 . Rotatably mounted in the bearings M^6 M^7 is a shaft M^8 which projects outwardly through an aperture M^9 in the housing L^4 and is controlled by the external handle or knob M^{10} provided with indicating symbols M^{11} and aligned with the opposed pointing member M^{12} . M^{14} is any suitable worm gear secured to the shaft M^8 and positioned between the bearings M^6 M^7 , the boss M^{15} of said worm gear being preferably held in frictional engagement with the bearing M^6 by means of the coil spring M^{16} about the shaft, held between the bearing member M^7 and the worm M^{14} .

It will be seen from the drawings, and for example from Fig. 4, that the angle or form of the opposed rack and worm are such that no normal thrust against the gauge plate will have any perceptible tendency to cause rotation of the shaft M^8 or the knob M^{10} .

M^{17} The worm gear, herein shown with a double

thread, though any other single or multiple threaded worm may be used, is in mesh with a rack bar N of circular cross-section, which supports the member M by means of the bearing members M^4 M^5 . The rack bar or rail N is supported and secured upon the flange K^1 of the frame K by the screws N^1 N^2 as illustrated in Figure 6. N^3 is an oil pad positioned within the oil pocket M^3 and is in contact with the underneath portion of the rack bar N . N^4 is a lug downwardly projecting and integral with the bearing M^4 to which is fastened one end of a coil spring N^5 . The opposite end of said spring is secured to an angular member N^6 supported by the screw N^2 its purpose being to hold the gauge plate rigidly at any point of adjustment.

It will be understood that the gauge plate assembly is moved along its supporting rack bar N by manipulating the external handle M^{10} which rotates the worm gear M^{14} , the teeth of which move along and between the opposed teeth N^7 of the rack bar N , the results being that the gauge plate is moved towards or away from the knife, depending on the direction of rotation of the worm gear. Rocking motion of the gauge plate assembly is prevented by means of the bearing members or pins N^{10} engaging the elongated bearing surfaces or bosses N^{11} downwardly projecting from the flange L^5 . I prefer to have one of such bearing members on each side of the supporting rack bar as illustrated in Figures 4 and 5. The pins N^{10} are held in the threaded bosses N^{12} integral with the flange K^1 and are adjustable by means of the screws N^{14} and lock nuts N^{15} .

It will be understood that when the gauge plate is advanced to the position shown in Figure 3, it masks the cutting edge of the knife and is in what I may call neutral position. The operator can then clean the face of the gauge plate and, in order to prevent possibility of the gauge plate slipping back and exposing the edge of the knife, I provide locking means for the shaft M^8 as shown particularly in Figures 3, 4 and 7. Referring to such figures, O is a slot in the collar or sleeve O^1 which is mounted upon the shaft M^8 by any suitable means for example by a set screw O^2 . O^3 is a recess in the bearing member M^6 , in which is mounted the locking ball O^4 normally outwardly thrust by the spring O^5 . The location of the slot O is such that when the gauge plate is in neutral position, the slot O overlies the aperture O^3 and receives the lock ball O^4 . The locking effect is sufficient to prevent unintended rotation of the shaft and collar for example by unintended contact of the arm or body with the handle M^{10} .

It will be seen from the drawings that the rack bar N is set at an angle in relation to the face of the gauge plate and preferably

is set at an angle of 45°. I may limit the travel of the gauge assembly, for example by the pin P secured to the collar O¹ which engages a pin P¹ on the bearing M⁶ in the neutral position and at the furthest point of travel of the gauge plate.

S is a cover or closure member, supported by the housing C and protecting a portion of the rotating knife E, said cover S being extended only slightly as at S¹ to allow a clear view of the opposite side of the operator.

Referring to Figures 8 and 9, I illustrate a variation of my device in which in the place of the gauge plate L shown in Figures 1 and 2 as integral with the supporting structure L⁴, I employ a separate and separately adjustable gauge plate L²⁰, adjustable in relation to L⁴. It is shown for example in Figure 9, as supported upon the forward and upwardly projecting portion L²¹, integral with or associated with the portion L⁴. Any suitable adjusting means may be employed but I herein illustrate screws L²² mounted upon the portion L²¹ and passing through the adjusting slots L²³ and the face plate member L²⁰.

These slots are preferably of such dimensions as to permit movement of the plate L²⁰ toward and away from the edge of the knife and also to permit some slight upward or downward or angular movement of the member L²⁰ in order to conform the arcuate portion L⁸ to the opposed edge of the knife.

It will be realized that whereas I have illustrated and described a practical and operative device, nevertheless many changes might be made in the size, shape, number and disposition of parts without departing from the spirit of my invention, and I therefore wish my drawings and description to be taken as in a broad sense illustrative and diagrammatic rather than as limiting me to my precise showing.

The use and operation of my invention are as follows:

I provide a generally vertical normally fixed guard plate, arcuately cut away to permit the penetration or the exposure of the edge of the rotary knife about a relatively restricted arc. The plane of the knife is tilted to bring the exposed edge generally into the plane of or close to the plane of the forward face of the guard plate. The knife is hollowed or sunk in order to permit its peripheral portion E⁴ to extend forwardly beyond the body of the knife and beyond the forward face of the guard plate. Generally aligned with the guard plate F is the adjustable gauge plate L¹ controlled by the worm gear M¹⁴ which in turn is controlled by rotation of the handle M¹⁰. The spring N⁵ has a braking action in that it constrains the gauge plate support, and thus the worm gear to frictional contact with the rack. By thus urging the opposed screw threaded members into frictional

contact it tends to hold the gauge plate rigidly at any point of adjustment and to prevent unintended displacement of the gauge plate as when the sleeve of the operator brushes against the knob. The face of the gauge plate L¹ may, if desired, be slightly bowed to conform to the curvature of the exposed knife edge due to the inclination of the axis of the knife or the tilting of the plane of the knife out of parallelism with the path of movement of the carriage.

The gauge plate is adjustable, in response to rotation of the worm gear, and moves toward and away from the path of the carriage H. The rack or guide rail N, upon which rides the gauge plate assembly, is preferably set at an angle of approximately 45°. Thus the excursion of the gauge plate in relation to the cutting edge of the knife is at a like angle. By using a worm gear and rack, I obtain a constant and uniform travel of the gauge plate towards and away from the knife edge and carriage in response to rotation of the handle M¹⁰. The gauge plate is held rigid by means of the springs M¹⁰ N⁵, which assure positive frictional engagement of the worm gear teeth with the rack teeth, and rocking motion of the gauge plate assembly upon the rack bar or rail N is eliminated by the precise adjustment of the guide pins N¹⁰ illustrated in Figure 5. Lubrication for the worm gear and rack is accomplished by the use of the oil pad N⁸.

The material to be cut is placed upon the carriage H and is moved, for the cutting excursion, from left to right as shown in Figures 1 and 3. The thickness of the slice is determined by the position of the right edge of the gauge plate L¹ in relation to the exposed cutting edge of the rotary knife, the slice passing through the aperture between the knife and gauge plate and dropping upon any suitable receiving plate, not shown in the drawings from which it may be manually removed.

In order to provide clear vision for the operator of the slicing machine of the opposite side of the machine, the upper edge of the vertical gauge plate is kept comparatively thin and in addition I prefer to limit the length of the cover S, said cover overhanging the gauge plate only for a short distance. Note that the upper edge of the gauge plate L is positioned generally at the level of the lower edge of the removable cover plate E. Therefore, when the user of the device sees that the work being sliced lies below the upper edge of the gauge plate he can know that it will clear the lower edge of the cover plate.

It will be observed that every movement of the operating knob gives exactly the same amount of movement to the gauge plate, in contrast to certain previous devices wherein the gauge plate is swingingly mounted, on links or the like, and a given movement of the operating knob would result in a varying

movement of the gauge plate, depending upon its particular position at the time of actuation of the knob.

The gauge plate may be adjusted in relation to the cutting plane, for example by the raising and lowering of the studs or supports N^{10} , by rotation of the screws N^{14} . The adjustment, when established, may be fixed by the lock nuts N^{15} . Since the members N^{10} are positioned at the front and rear respectively of the supporting structure L^4 it is apparent that if the rear one is raised the top of the face plate will be tilted forward and if the rear is lowered it will be tilted back.

Further adjustment of the face plate will be obtained, in the form shown in Figures 8 and 9, by the adjusting slots, shown as formed in the face plate, which permits the face plate to be moved, in relation to the support L^4 toward and away from the edge of the knife. This adjustment is frequently of importance, to compensate for wear on the knife. A certain range of vertical adjustment of the gauge plate is also permitted by the relative size of the slots and screws passing therethrough.

I claim:

1. In a slicing machine having a rotary knife and means for rotating it, a material supporting carriage and means for moving it across the face of said knife, a gauge plate lying in a plane substantially parallel with the path of movement of such carriage, and means for moving said gauge plate toward

30 and away from the path of said carriage along a path inclined thereto, said means including a rack associated with said gauge plate, a rotary member in mesh therewith and means for rotating it.

2. In a slicing machine having a rotary knife and means for rotating it, a material supporting carriage and means for moving it across the face of said knife, a gauge plate lying in a plane substantially parallel with the path of movement of such carriage, and means for moving said gauge plate toward and away from the path of said carriage along a path inclined thereto, said means including a rack associated with said gauge plate, and inclined thereto in parallelism with the desired path of movement of the gauge plate, a shaft generally parallel with the movement of the carriage and means for rotating it, and a rotary member thereon, in mesh with said rack.

3. In a slicing machine having a rotary knife and means for rotating it, a material supporting carriage and means for moving it across the face of said knife, a gauge plate lying in a plane substantially parallel with the path of movement of such carriage, and means for moving said gauge plate toward and away from the path of said carriage along a path inclined thereto, said means including a rack associated with said gauge

plate, a worm in mesh with said rack and means for rotating said worm.

4. In a slicing machine having a rotary knife and means for rotating it, a material supporting carriage and means for moving it across the face of said knife, a gauge plate lying in a plane substantially parallel with the path of movement of such carriage, and means for moving said gauge plate toward and away from the path of said carriage along a path inclined thereto, said means including a rack associated with said gauge plate, a worm in mesh with said rack and means for rotating said worm, the axis of said worm being inclined to the path of movement of said rack.

5. In a slicing machine having a rotary knife and means for rotating it, a material supporting carriage and means for moving it across the face of said knife, a gauge plate lying in a plane substantially parallel with the path of movement of such carriage, and means for moving said gauge plate toward and away from the path of said carriage along a path inclined thereto, including a closed housing rearwardly extending from said gauge plate, a rack associated with said housing, a shaft penetrating said housing and a rotary member thereon, in mesh with said rack, and means, operable from without said housing, to rotate said shaft and rotary member.

6. In a slicing machine having a rotary knife and means for rotating it, a material supporting carriage and means for moving it across the face of said knife, a gauge plate lying in a plane substantially parallel with the path of movement of such carriage, and means for moving said gauge plate toward and away from the path of said carriage along a path inclined thereto, including a closed housing rearwardly extending from said gauge plate, a rack within said housing, a shaft penetrating said housing, and a worm thereon in mesh with said rack and means for rotating said shaft and worm.

7. In a slicing machine having a rotary knife and means for rotating it, a material supporting carriage and means for moving it across the face of said knife, a gauge plate lying in a plane substantially parallel with the path of movement of such carriage, and means for moving said gauge plate toward and away from the path of said carriage along a path inclined thereto, including a closed housing rearwardly extending from said gauge plate, a rack bar within said housing, a shaft penetrating said housing and a rotary member on said shaft in mesh with said rack bar and adjustable bearing and supporting means for said housing.

8. In a slicing machine having a rotary knife and means for rotating it, a base member, a guard plate upwardly projecting therefrom, a carriage and means for moving it

5 across the face of said guard plate, a gauge plate and means for moving it toward and away from the path of said carriage, a housing to the rear of said guard plate, and a removable cover member, overlying said housing and the upper edge of said guard plate.

9. In a slicing machine, a rotary knife and means for rotating it, the forward face 10 of said knife being recessed, a guard plate positioned in front of said knife, the plane of said knife being slightly inclined to the plane of said guard plate, said guard plate penetrating the knife recess at one side of 15 said knife, a housing to the rear of said knife and guard plate and a removable cover therefor overlying the upper edge of said guard plate, a carriage and means for moving it across the face of said guard plate, a gauge 20 plate and means for moving it toward and away from the path of said carriage, said gauge plate being positioned, throughout substantially its entire width, out of vertical alignment with the housing cover.

25 10. In a slicing machine, a rotary knife and means for rotating it, the forward face of said knife being recessed, a guard plate positioned in front of said knife, the plane of 30 said knife being slightly inclined to the plane of said guard plate, said guard plate penetrating the knife recess at one side of said knife, a housing to the rear of said knife and guard plate and a removable cover therefor overlying the upper edge of said 35 guard plate, a carriage and means for moving it across the face of said guard plate, a gauge plate and means for moving it toward and away from the path of said carriage, said gauge plate being positioned, throughout 40 substantially its entire width, out of vertical alignment with the housing cover, the upper edge of said gauge plate lying substantially at the level of the uppermost portion of the 45 arc of exposure of the knife edge.

50 11. In a slicing machine having a rotary knife and means for rotating it, a material supporting carriage and means for moving it across the face of said knife, a gauge plate lying in a plane substantially parallel with 55 the path of movement of such carriage, and means for moving said gauge plate toward and away from the path of said carriage along a path inclined thereto, and means for adjusting said gauge plate in relation to the cutting plane, including a plurality of vertically adjustable supports.

12. In a slicing machine having a rotary knife and means for rotating it, a material supporting carriage and means for moving 60 it across the face of said knife, a gauge plate lying in a plane substantially parallel with the path of movement of such carriage, and means for moving said gauge plate toward and away from the path of said carriage along a path inclined thereto, including a

carrier member upon which said gauge plate is mounted and means for adjusting said face plate in relation to the cutting plane of the knife, including vertically adjustable supports for said carrier.

13. In a slicing machine having a rotary knife and means for rotating it, a material supporting carriage and means for moving it across the face of said knife, a gauge plate lying in a plane substantially parallel with 70 the path of movement of said carriage, a support for said gauge plate and means for moving said support and gauge plate toward and away from the path of said carriage along a path inclined thereto, and means for adjusting the generally horizontal plane along which said support moves.

14. In a slicing machine, a rotary knife and means for rotating it, a gauge plate and a guard plate lying in generally parallel 75 planes, the axis of the knife being tilted from perpendicularity to said gauge and guard plate, the cutting arc of the knife being thereby positioned forwardly of the plane of the guard plate, the body of the knife lying 80 behind the guard plate, the face of the gauge plate being bowed to conform generally to the contour of the cutting arc of the knife, a material supporting carriage and means for moving it across the face of the knife and 85 means for moving the gauge plate toward and away from the path of the carriage, along a rectilinear path inclined thereto.

15. In a slicing machine, a rotary knife and means for rotating it, a material supporting carriage and means for guiding across the face of the knife, a guard plate for the forward face of the knife, a gauge plate lying in a plane substantially parallel with 90 that of the guard plate and means for moving the gauge plate toward and away from the cutting plane of the knife along a path inclined to the path of movement of the carriage, including a rack associated with the gauge plate and a quick thread screw threaded member opposed thereto and a manual control member adapted to rotate said quick 95 thread screw threaded member.

16. The structure of claim 15 characterized in that a rotation of the manual control member through an arc of less than 360° moves the gauge plate throughout its entire excursion of adjustment, said control member being adapted, in response to any given unit or arc of rotation, to move said gauge plate a 100 uniform distance toward or away from the path of movement of the carriage, said units being calibrated about the periphery of said manual control members.

17. In a slicing machine a rotary knife and means for rotating it, a material supporting carriage and means for guiding it across the face of said knife, a gauge plate lying in a plane substantially parallel with 105 the path of movement of said carriage, and 110

means for moving said gauge plate toward and away from the path of the carriage, along a rectilinear path, said means including a shaft, a manual control member for said shaft, and a gear connection between said shaft and said gauge plate including screw threaded members, and braking means, effective at substantially all positions of the gauge plate, adapted to hold the gauge plate against unintended movement, including yielding means for maintaining a predetermined frictional contact between the opposed screw threaded members, said screw threaded members including a quick thread screw threaded member rotatable with the shaft and an opposed screw threaded member associated with the gauge plate.

18. In a slicing machine a rotary knife and means for rotating it, a material supporting carriage and means for guiding it across the face of said knife, a gauge plate lying in a plane substantially parallel with the path of movement of said carriage, and means for moving said gauge plate toward and away from the path of the carriage, along a rectilinear path inclined thereto, said means including a shaft, a manual control member for said shaft, and a gear connection between said shaft and said gauge plate, said shaft being adapted to move said gauge plate through its entire effective excursion in response to the rotation of said manual control member through an arc of less than 360° , said gear connection being adapted to cause movement of the gauge plate in response to rotation of said shaft and to prevent rotation of said shaft in response to movement of said gauge plate.

Signed at Indianapolis county of Marion, and State of Indiana, this 23rd day of February, 1928.

WILLIAM J. CAMPBELL.
